ATTORNEY

UNITED STATES PATENT OFFICE

CHARLES G. WILKINSON, OF NEW YORK, N. Y.

FLAGPOLE AND THE LIKE

Application filed November 11, 1929. Serial No. 406,232.

This invention relates to new and useful improvements in a flag pole or the like joint.

The invention has for an object the provision of a device of the class mentioned which is of simple durable construction, dependable in use and efficient in action, and which can be manufactured and sold at a reasonable cost.

The invention proposes an upper pole section telescopedically engaged within a lower pole section, a cup secured within the lower pole section and formed with an outer chamfered top edge engaging an inner chamfered bottom edge on said upper pole section for supporting the upper pole section and for collecting rain water and the like and for preventing any leakage of rain water into the lower pole section and consequent decay to building or foundation.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a fragmentary vertical sectional view of a flag pole joint constructed according to this invention.

Fig. 2 is an enlarged detailed view of the cup used in Fig. 1.

Fig. 3 is a view similar to Fig. 1, but illustrating another embodiment.

Fig. 4 is another view similar to Fig. 1, but illustrating a still further embodiment.

Fig. 5 is an enlarged detailed view similar to a portion of Fig. 1, but illustrating a modification.

The flag pole joint consists of an upper pole section 10 telescopedically engaged within a lower pole section 11, a cup 12 secured within the lower pole section and formed with an outer chamfered top edge 13 engaging an inner chamfered bottom edge 14 on said upper pole section 10 for supporting the upper pole section and for collecting rain water and the like to reevaporate and for preventing any leakage of rain water into the lower pole sec-

tion and consequent decay to building or foundation.

The said cup 12 is provided with a plurality of peripheral ridges 15 completely extending around its circumference and providing a water tight joint when engaged within the lower pole section 11. The engagement is accomplished by heating and hydraulically pressing the lower pole section around the cup and then allowed to cool. In this manner the lower pole section is shrunk upon the cup and the peripheral ridges 15 are depended upon to prevent the passage of water between the adjacent faces of the cup and the lower pole section.

In Fig. 3 another embodiment of the invention has been disclosed in which a means is provided for draining collected water from the cup 12'. This means is accomplished by providing the cup 12' and the lower pole section with aligned apertures 16. The passage produced by these apertures extends from the bottom of the cup downwards so that the cup may be completely drained.

In Fig. 4 another modified form has been illustrated in which a second means has been shown for attaching the cup within the lower pole section. The attachment is accomplished by rivets 17 arranged thru the cup and thru the lower pole section.

In the modified form of the device illustrated in Fig. 5, a means has also been provided for adapting the upper pole section for engaging firmly in slightly oversized lower pole sections to obviate extreme care and accuracy in manufacture. The said means consists of a plurality of support plates 18 hingedly mounted at their upper ends upon the lower end of the upper pole section 10' and formed with inner chamfered lower ends 14' engaging the outer chamfered upper edge 13 of the cup 12, and means for urging the plates slightly outwards. The latter means consists of a strong coaxial spring 19 arranged on each of the pivot points of the support plates 18 and capable of slightly urging the plates outwards. The plates must be manually forced together when the upper pole section is inserted within the lower pole section and the spreading

action of the springs 19 cause the edges of the support plates provided with the chamfered edges to engage in the corners produced by the upper chamfered edge 13 of the cup with the adjacent face of the lower pole section.

In operation of the device, the lower pole section may be attached upon a roof or any other support. A flag may be supported upon the top of the upper pole section. Rain water and the like running down the outer surface of the upper pole section may collect in the cup 12' and may drain out thru aperture 16.

15 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

25 1. A flag pole or the like joint, comprising an upper pole section telescopically engaged within a lower pole section, a cup secured within the lower pole section and formed with an outer chamfered top edge engaging an inner chamfered bottom edge on said upper pole section for supporting the upper pole section and for collecting rain water and the like to reevaporate and for preventing leakage of rain water into the lower pole section and consequent decay and damage to building or foundation, said cup being provided with a plurality of peripheral ridges arranged for engaging the lower pole section and providing a water tight joint between these parts.

40 2. A flag pole or the like joint, comprising an upper pole section telescopically engaged within a lower pole section, a cup secured within the lower pole section and formed with an outer chamfered top edge engaging an inner chamfered bottom edge on said upper pole section for supporting the upper pole section and for collecting rain water and the like to reevaporate and for preventing leakage of rain water into the lower pole section and consequent decay and damage to foundation or building, said cup being provided with a peripheral ridge firmly engaging the metal of the lower pole section by reason of the lower pole section being shrunk thereon.

45 3. A flag pole or the like joint, comprising an upper pole section telescopically engaged within a lower pole section, a cup secured within the lower pole section and formed with an outer chamfered top edge engaging an inner chamfered bottom edge on said upper pole section for supporting the upper pole section and for collecting rain water and the like to reevaporate and for preventing

leakage of rain water into the lower pole section and consequent decay and damage to foundation or building, and means for adapting the upper pole section for engaging firmly in slightly oversized lower pole sections to obviate extreme care and accuracy in manufacture, said means including support plates hingedly mounted and normally urged slightly outwards.

50 In testimony whereof I have affixed my signature.

CHARLES G. WILKINSON.
